UNITED STATES PATENT OFFICE

JOHN M. McCLOATCHIE, OF NEW YORK, N. Y., ASSIGNOR TO THE BORDEN COMPANY, OF NEW YORK, N. Y., A CORPORATION OF NEW JERSEY

AIR NOZZLE

Original application filed April 17, 1930, Serial No. 444,963. Divided and this application filed October 3, 1931. Serial No. 566,662.

This invention relates to a nozzle adapted for directing an air stream against milk-can covers or similar articles to dry the same after they have been subjected to a washing, steaming or other like sterilizing treatment. This application is a division of my co-pending application, Serial No. 444,963, filed April 17, 1930. In that application is described an apparatus for washing, sterilizing and drying milk-cans and the covers therefor. After the cans and their covers have been washed and sterilized they are dried by an application of air. The present structure relates to the nozzle which directs an air blast against the under surfaces of such wet milk-can covers or similar articles to dry the same.

The object of this invention is to provide an improved drying nozzle which will serve to direct the air blast against the various under surfaces of the cover, and which will be provided with suitable exit ducts whereby the air that becomes moisture-laden by its contact with the wet can cover is directed through said exit ducts and passes out through the same without impeding the flow of or mixing with the dry air which is being directed against the can cover.

The preferred form of the invention is illustrated in the accompanying drawing, in which Fig. 1 is a sectional view through a drying nozzle made in accordance with this invention, and Fig. 2 is a plan view of the same.

In Fig. 1 is shown one of the can covers adapted to be dried by the nozzle. The cover is of well-known type and has a flanged top portion 3 from which extends a cylindrical or tubular neck portion 4 of less diameter than the flanged top portion. This cylindrical neck portion 4 fits within the mouth of the can. During the drying operation, the cover is usually supported on rails 5 and 6 and is preferably held at an angle as indi-

cated in Fig. 1 so that access to the inside of the cover and to the under portion of the flanged part 3 is had by the air blast directed by the drying nozzle.

After a cover has been washed and sterilized it is moved along on its supports 5 and 6 until it reaches a position over the drying nozzle. The nozzle comprises an outer, annular discharge orifice 7 and a central discharge orifice 8. An air blast is forced through both of these discharge orifices from the supply pipe 9 which is connected to a suitable source of air supply. The annular orifice 7 is formed between an outer annular wall consisting of the conical section 10 and the cylindrical section 11, and an inner wall consisting of the conical section 12 and cylindrical section 13. The contracted lower end of the outer conical wall 10 is connected to the air supply pipe 9. The inner wall of the annular discharge orifice 7 is supported by and is held spaced apart from the outer wall by means of the several short exit pipes 14 which pass through the conical wall sections. The central discharge orifice 8 is formed by a pipe 15 supported at its inner or lower end by the contracted lower end of the inner conical wall section 12. Between the pipe 15 and the inner wall sections 12 and 13 is an annular exit passageway 16 which discharges through the pipes 14.

The mode of operation of the improved air nozzle will be readily understood from a consideration of Fig. 1 in which the various air currents are indicated by the arrows. The blast of air passing through the central duct 8 is conducted against the interior surfaces of the cover, and said air becoming moisture-laden on contact with the cover, is directed by those surfaces into the annular exit passageway 16 whence it is discharged into the atmosphere through the pipes 14. The air passing from the supply pipe 9 through the annular orifice 7 is directed partly against the inter-

- rior or inner surfaces of the cover and partly against the outer surfaces of the cylindrical portion 4 thereof and also against the under surface 17 of the flanged part of the cover.
- 5 The air directed into the interior of the cover through the annular duct 7 is redirected into the exit passageway 16 and thence through the pipes 14, whereas the air directed against the exterior surfaces of the cover picks up 10 the moisture therefrom and carries it directly into the atmosphere. It has been found unnecessary to direct an air blast against the top of the cover 3.

What I claim is:—

- 15 1. A device for drying a can cover that is provided with a tubular neck portion and a top portion to the underside of which the tubular portion is connected, said device consisting of a nozzle having a central duct for 20 directing a stream of air against the central part of the lower surface of the top of the cover, an annular duct for directing a stream of air against the part of the lower surface of the cover to which the tubular neck is 25 connected, and an annular outlet space located between the central duct and the annular duct for receiving air deflected by the cover, and discharge openings leading from the annular outlet space.
- 30 2. A nozzle for directing streams of air against the under surface of a can cover that has a circular top portion and a tubular neck portion secured to the under surface of the top portion, said nozzle comprising an annular duct for directing air against the part of the under surface of the cover to which the annular neck portion is secured, a central duct for directing air against the center of the under surface of the cover, and an annular outlet space formed between the annular duct and the central duct for receiving air deflected by the cover, and passageways leading from the annular outlet space through the annular duct.
- 35 3. An air nozzle for drying milk-can covers or similar articles, said nozzle having a pair of concentric discharge orifices for directing an air blast against a cover, a chamber located between the orifices for receiving the air blast deflected by the cover, and outlet passages leading from said chamber.
- 40 4. An air nozzle for drying can covers and the like, provided with an air supply pipe, an enlarged head thereon having an outer wall, an inner wall located within the outer wall and spaced therefrom to provide an annular discharge orifice between the walls, a discharge pipe located within the inner wall and spaced therefrom to provide a chamber 45 between it and said inner wall, and outlet openings leading from said chamber and through the inner and outer walls.
- 45 5. An air nozzle for drying can covers and the like, provided with an air supply pipe, a head thereon having an outer wall formed

with a cylindrical portion and a conical portion, a similarly shaped inner wall disposed within the outer wall and spaced therefrom, a discharge pipe located within the inner wall and in registration with the air supply pipe to receive the air flow therefrom, said discharge pipe being spaced from the inner wall to provide a chamber between it and said inner wall for receiving a deflected air blast, and outlet openings leading from said chamber through the inner and outer walls.
